PROCESS OF PRODUCING VENETIAN BLIND
LADDER TAPESchuyler J. Taylor, Portland, Conn., assignor to
The Russell Manufacturing Company, Middle-
town, Conn., a corporation of Connecticut

Application March 25, 1939, Serial No. 264,260

4 Claims. (Cl. 91—67.9)

This invention relates to improvements in processes of producing Venetian blind ladder-tape with the outside faces of the two body or main tapes of the ladder-tape of different colors.

One object of this invention is to provide an improved process of producing Venetian blind ladder-tape having two woven main tapes interconnected by ladder-rungs interwoven with the two main tapes, and having the outside faces of the two main tapes of different colors.

With the above and other objects in view, as will appear to those skilled in the art from the present disclosure, this invention includes all features of the said disclosure, which are novel over the prior art.

In the accompanying drawings forming part of the present disclosure, in which certain ways of carrying out the invention are shown for illustrative purposes:

20 Fig. 1 is a diagrammatic side elevation illustrating one way of carrying out the present invention;

Fig. 2 is a top plan view of Fig. 1;

Fig. 3 is a cross sectional view on line 3—3 of Fig. 1;

Fig. 4 is a cross sectional view on line 4—4 of Fig. 1;

Fig. 5 is a fragmentary cross sectional view on line 5—5 of Fig. 1;

30 Fig. 6 is a perspective view of a fragment of two-color ladder-tape made in accordance with the present invention; and

Fig. 7 is a view similar to Fig. 5 of a modified form of the invention.

35 In the description and claims, the various parts and steps are identified by specific names for convenience, but they are intended to be as generic in their application as the prior art will permit.

40 Referring to Figs. 1 to 6 of the drawings which illustrate one way of carrying out the present invention, the Venetian blind ladder-tape 10 of usual form, has two woven body or main tapes

45 11 and 12 interconnected by ladder-rungs 13 interwoven with the two main tapes 11 and 12, the two main tapes being of the same surface appearance, whether being due to being uncolored or colored. In order to produce Venetian blind

50 ladder-tape of attractive appearance, I apply any desired color or colors to one or both of the outer faces 14 and 15 respectively, of the main tapes 11 and 12. Such expressions as "two colors" or "different colors" is intended to include

55 where one surface appearance is different from

another, regardless of whether either or both contain any true "color."

As the ladder-tape 10 travels from left to right of Figs. 1 and 2, the lifter-flanges 16 and 17 of the guide-member 18 engage the upper main tape 5 12 and lift the edge portions 19 and 20 thereof upwardly as shown in Figs. 1, 2 and 3, to permit paper or the like shield-tapes 21 and 22, which are fed downwardly and around pins or rollers 23 and 24, to pass between the edge portions of 10 the main tapes 11 and 12 and thence into the guides 25 and 26 of the guide-member 18. As the tape 12 passes beyond the rear edges of the lifter-flanges 16 and 17, the edge portions 19 and 20 of the tape 12 flatten out again somewhat as 15 shown in Figs. 1, 2 and 4, and as the main tapes 11 and 12 and paper shield-tapes 21 and 22 pass beyond the end of the rear end 27 of the guide-member 18, they pass between idler-rollers 28 and 29 and then between a printing-roll or roller 20 30 and a pressure-roll or roller 31, with the paper shield-tapes 21 and 22 located between the edges of the main tapes 11 and 12 and extending oppositely outwardly a considerable distance from the side-edges of the main tapes 11 and 12, as shown 25 in Fig. 5.

The printing-roll 30 is preferably of metal such, for example, as copper, and has a knurled portion 32 which constitutes the ink-applying surface of the printing-roll 30, the ink being applied to the knurled surface 32 in any suitable way, as for example by means of an inking-brush 33. Any suitable ink may be used, such for example as water-proof lacquer ink. The pressure-roll 31 preferably has a resilient surface portion 34 of rubber or other suitable material to aid in securing a more perfect and uniform printing of the surface 14 of the main tape 11. 35

40 After the ladder-tape passes beyond the printing-roll 30, it may be given a sufficient distance of travel to permit it to dry in the air or it may be passed through a suitable heating oven to hasten the drying. If it is only desired to have the one color applied to the surface 14 of the main tape 11 and to leave the surface 15 of the other tape with its color as woven, then the ladder-tape is wound up on a suitable roll for storage or sale in any suitable or usual manner.

If, however, it is desired to also print the surface 15 of the main tape 12, this can be done by 50 running the ladder-tape past a second printing-roll (not shown) arranged to print the top surface of the ladder-tape shown in Fig. 1, or else by feeding the ladder-tape with a 180° twist to bring the top surface 15 of the tape 12 down to 55

the under side to engage a printing-roll in a similar position to the printing-roll 30 shown in Fig. 1.

During the printing operation, the paper shield-tapes 21 and 22 protect the main tape 12 from having ink applied to the edges thereof, as will be seen from Fig. 5, since such ink as oozes somewhat beyond the knurled portion 32 of the printing-roll 30 will get on the under surfaces 10 of the paper tapes 21 and 22, and will thus be prevented from getting on to the rubber portion 34 of the pressure-roll 30, from which ink could be readily transferred to the edge portions of main tape 12, if not protected against such action by the paper tapes. The paper shield-tapes or the like 21 and 22 can be either discarded after having been once used, or the paper tapes can be in the form of endless bands or aprons to be fed back to the original position for successive 15 repeated use.

Instead of applying the ink by printing methods, the ink can be applied by any other suitable process such, for example, as by being sprayed upon the tape, preferably from the under side 25 of the tape.

In the form of the invention illustrated in Fig. 7, the two main or body tapes 35 and 36 of the Venetian blind ladder-tape 37 are preferably woven so as to have the main tape 36 somewhat 30 narrower than the main tape 35. In this form of the invention, the main tapes 35 and 36 are not separated during the printing operation, but a shield in the form of a wide paper tape or the like 38 extends entirely across and beyond the 35 ladder-tape 37 as shown in Fig. 7, and has the shield-portions 39 and 40 to protect the rubber portion 34 of the pressure-roll 31 from getting ink thereon from the printing-roll 30 during the printing operation, and thus avoiding having the 40 rubber portion of the pressure-roll 30 transferring ink to the side and rear of the edge portions of main tape 36. While the main tape 36 could be of the same width as the main tape 35, by having it somewhat narrower as illustrated in Fig. 7, 45 with the side edges of the tape 36 somewhat back away from the side edges of the tape 35, there is less tendency for ink to get upon the side edges of the tape 36. The shield or apron tape 38 can be of endless form so as to be used over and over 50 again in a similar manner as that described concerning the form of the invention illustrated in Figs. 1 to 6.

The invention may be carried out in other specific ways than those herein set forth without departing from the spirit and essential characteristics of the invention, and the present embodiments are, therefore, to be considered in all respects as illustrative and not restrictive, and all 55

changes coming within the meaning and equivalency range of the appended claims are intended to be embraced therein.

I claim:

1. The process of producing Venetian blind 5 ladder-tape having two woven main tapes interconnected by ladder-rungs secured to the two main tapes, and having the outside faces of the two main tapes of different colors, comprising: providing Venetian blind ladder-tape having two 10 woven main tapes with their outside faces of the same color and with ladder-rungs interwoven with said main tapes; causing said ladder-tape to travel longitudinally of itself; and applying coloring material to the outside face of one of the 15 said two main tapes while protecting the other main tape from said coloring material, by traveling tape-masks interposed between the edges of the said two main tapes.

2. The process of producing Venetian blind 20 ladder-tape having two woven main tapes interconnected by ladder-rungs secured to the two main tapes, and having the outside faces of the two main tapes of different colors, comprising: causing ladder-tape to travel longitudinally of 25 itself; and applying coloring material to the outside face of one of the said two main tapes while protecting the other main tape from said coloring material, by traveling mask means interposed between the edges of the said two main tapes. 30

3. The process of producing Venetian blind ladder-tape having two woven main tapes interconnected by ladder-rungs secured to the two main tapes, and having the outside faces of the two main tapes of different colors, comprising: providing Venetian blind ladder-tape having two 35 woven main tapes with their outside faces of the same color and with ladder-rungs interwoven with said main tapes; causing said ladder-tape to travel longitudinally of itself; and applying coloring material to the outside face of one of the said two main tapes by roll-printing means while protecting the other main tape from said coloring material, by traveling mask means interposed between the edges of the said two main tapes. 40

4. The process of producing Venetian blind ladder-tape having two woven main tapes interconnected by ladder-rungs secured to the two main tapes, and having the outside faces of the two main tapes of different colors, comprising: causing ladder-tape to travel longitudinally of 45 itself; and applying coloring material to the outside face of one of the said two main tapes by roll-printing means while protecting the other main tape from said coloring material, by traveling tape-masks interposed between the edges of the said two main tapes. 50

SCHUYLER J. TAYLOR.
